CLAIM

The ornamental design for a kettlebell, as shown and described.

DESCRIPTION

FIG. 1 is a front side perspective view of a kettlebell showing my new design.

FIG. 2 is a front view of a kettlebell.

FIG. 3 is a rear view of a kettlebell.

FIG. 4 is a left side view of a kettlebell.

FIG. 5 is a right side view of a kettlebell.

FIG. 6 is a top view of a kettlebell.

FIG. 7 is a bottom view of a kettlebell; and,

FIG. 8 is a rear side perspective view of a kettlebell.

The broken lines in the drawings depict portions of the kettlebell that form no part of the claimed design.

The Nike Swoosh forming a part of the claimed design is a registered trademark of Nike.

1 Claim, 8 Drawing Sheets
